UNITED STATES PATENT OFFICE.

JOHN RIIKONEN, OF CHICAGO, ILLINOIS, ASSIGNOR TO CHARLES A. ERICKSON, OF CHICAGO, ILLINOIS.

HOLDER AND PUNCH FOR PRICE OR PAY CHECKS.

1,248,917.

Specification of Letters Patent. Patented Dec. 4, 1917.

Application filed June 6, 1917. Serial No. 173,196.

To all whom it may concern:

Be it known that I, JOHN RIIKONEN, a citizen of the United States, and a resident of Chicago, in the county of Cook and State of Illinois, have invented certain new and useful Improvements in a Holder and Punch for Price or Pay Checks, of which the following is a specification.

This invention relates to improvements in a holding and punching device for that class of pay checks or tickets used in a large number of restaurants, and sometimes in other lines of business, which checks or tickets have displayed on one of their faces 10 in a row along one or both of their edges, a series of numerals some of which increase numerically or by digits, while others thereof usually increase from 5, in multiples of 5, to 100 or above. These checks or tickets 15 are usually formed by being placed one on the other into tablets or pads, in such a way, that one of the checks or tickets may be removed at a time when it is necessary to indicate thereon, by punching or marking 20 out one of the numbers, the amount to be paid to the cashier for the meal which has been served or as the price of an article or articles which have been purchased. The 25 numerals on the checks or tickets, which are arranged numerically or by digits are employed to indicate the number of the waiter or salesman who delivers the check or ticket to the customer or patron, and one of said numerals is usually punched or marked out 30 to designate the waiter or salesman who 35 delivers said check.

The principal object of the invention, is to provide a holder and punch of the above-named general character, which shall be 40 simple and inexpensive in construction, strong, durable and efficient in operation, with its parts so made and arranged that it can be conveniently fastened to a waistband or belt on the body of the user and in such a position that the checks held thereby will be protected from accidental dislocation, yet may be readily reached for removal 45 from the holder or tablet one at a time.

A further object of the invention, is to

provide means for punching the checks accurately at the desired points by the use of one hand only, if desired.

Other objects and advantages of the invention, will be disclosed in the subjoined description and explanation.

In the accompanying drawing which serves to illustrate an embodiment of the invention,

Figure 1, is a plan view of the device, showing a tablet of checks held thereby.

Fig. 2, is a side view thereof.

Fig. 3, is a longitudinal sectional view taken on line 3—3 of Fig. 1, looking in the direction indicated by the arrows.

Fig. 4, is a cross-sectional view taken on line 4—4 of Fig. 2, looking in the direction indicated by the arrows, and

Fig. 5, is a detached view of one of the checks as it will appear after being punched by the device.

Like numerals of reference, refer to corresponding parts throughout the different views of the drawing.

The body or casing of the device is designated as a whole, by the reference numeral 75 10, and includes an elongated flat piece of metal 11 which forms the bottom of the holder for a tablet or pad 12 of checks or tickets 13, and a side plate 14 which forms the side wall of the holder for the tablet 80 or pad. As is clearly shown in Fig. 2 of the drawing, the plate 14 is tapered from one of its ends to a point near its other end, thus exposing a portion of one of the sides 85 of the pad or tablet 12 so that the checks 13 forming the same may be readily reached and removed from the pad, one at a time. By reference to Fig. 3 of the drawing, it will be seen that the member 11 of the body 90 or casing is bent near one of its ends to form a substantially rectangular casing or box 15 and that the upper horizontal portion of said member 11 and box is projected longitudinally with respect to the inner lower portion of the member 11 or bottom of the 95 holder and in parallelism therewith, as shown at 16 for the purpose to be presently explained. Secured to the upper surface of

the member or bottom 11 of the tablet holder is a spring 17 which projects at its free end to a point near the inner wall of the box 15 and has its free portion upwardly deflected 5 to rest against the lowermost check of the pad or tablet as will be readily understood by reference to Fig. 3 of the drawing. The inner wall of the box 15, or the wall thereof adjacent to the inner end of the tablet 12, 10 when the same is in position in the holder therefor, is formed by means of a vertical plate 18 which has at its upper portion a horizontal extension 19 underlying the extension 16 of the member 11 and may be 15 soldered or otherwise secured to the last named extension for the purpose of reinforcing the same. As shown the wall or plate 18 extends upwardly from the lower portion of the box 15 at the inner end of 20 the side-plate 14 and this closes the box 15 and besides provides a wall against which the inner end of the tablet 12 may abut. That portion of the box 15 adjacent to the side plate 14 of the holder, which portion 25 will be termed the front part of the device, is closed by the plate or member 19^a which has an inturned flange 20 vertically secured to the inner surface of the wall of the box 15 opposite the inner end of the side-plate 14, see Figs. 3 and 4 of the drawing. The plate or member 19^a is provided with a vertically disposed guide-way 21 which is substantially V-shaped in cross-section and has its upper end open for the reception and 30 operation of a similarly shaped plunger or punch 22 which has its lower end slightly inwardly beveled as at 23 to correspond with the inclination or beveled upper portion of an opening 24 in the lower portion of the 35 guide-way 21 for the plunger or punch. Secured at one of its ends to the flange 20 of the member 19 is a coiled spring 25 which is located within the box 15 and has its other end secured to the upper portion of the 40 plunger or punch 22 just below a head or thumb piece 26 with which the upper portion of the plunger is provided, for the purpose of depressing the same. The wall of the box or casing 15 opposite the member 19^a and guide-way 21, is formed by 45 means of a plate or strap 27 which is provided at its lower portion with a horizontal extension 28 which is fastened by means of a screw 29 to the bottom of the box or casing 15 and extends over an opening in the lower end of the guide-way 21 so as to close the same. The upper portion of the plate or strap 27 is provided with a hook 30 to engage a waist-band or belt or pocket of 50 the user.

Each of the checks or tickets 13 forming the pads or tablets 12 is transversely perforated or weakened near one of its ends as at 31, see Fig. 3, so that when the tablet

or pad is placed in the holder consisting 60 of the elongated member 11, side plate 14, end wall 18, top 16 and spring 17, said perforated or weakened portions will be located at the free edges of the extensions 16 and 19, to the end that the pressure of 70 the spring 17 against the bottom of the stub end of the pad will firmly hold the top of the pad against said extensions thus enabling the checks or tickets to be torn off one at a time. 75

From the foregoing and by reference to the drawings, it will be readily understood and clearly seen, that the hook 30 of the device may be placed over a belt or waist-band or in the vest pocket of the user, when 80 it is apparent that the device will be held in substantially a horizontal position with one of the sides of the tablet against the body of the waiter or user, while the other side of the tablet will be protected by the 85 side-plate 14, yet in such a manner, as to permit the checks or tickets 13 to be easily reached and torn off one at a time. When it is desired to punch out a number or numbers on the check, this can be done by placing the torn off check horizontally in the flared opening or slot 24, when by depressing the punch 22 by applying pressure to the head 26 thereof, it is evident that a V-shaped opening or openings will be formed 95 in the edge or edges of the check so as to indicate the number or numbers desired.

The clippings or pieces punched out of the checks will be retained by the box 15 thus preventing them falling on the floor, 100 and it is obvious that they can be removed from the box or casing by removing the plate or strap 27, or if desired, the tablet 12, it being understood that the plate 18 does not entirely close the opening in the 105 box 15 in which it is located.

Having thus fully described my invention, what I claim as new and desire to secure by Letters Patent is—

1. A holder and punch for checks or tickets consisting of a body having at one of its ends an overlying part and a casing, a guide-way in one of the walls of the casing having an opening near one of its ends and a punch slidably mounted in said guide-way. 110

2. A holder and punch for checks or tickets consisting of an elongated body having at one of its edges a transversely extended overlying member and a casing, a guide-way in one of the walls of said casing having an opening near one of its ends, a spring on the floor of the body, and a spring-actuated punch slidably mounted in said guide-way. 115

3. A holder and punch for checks or tickets consisting of an elongated body angular in cross-section having at one of its ends an 120

abutment and a part extended transversely thereof near one end of said abutment, a casing on the body at said end, a guide on one of the walls of said casing having an opening near one of its ends, a spring on the floor of the body, a punch slidably mounted on said guide, and a spring located

within the casing and secured at one of its ends to the same and at its other end to said punch.

JOHN RIIKONEN.
